UNDERGARMENT

Henry Virgil Oldham, McRoberts, Ky.

Application February 4, 1947, Serial No. 726,371

6 Claims. (Cl. 2—78)

1

This invention relates to improvements in undergarments and more especially unionsuits.

Underclothing of a weight that will insure comfort for other parts of the body is not sufficient for the spine, which because of its location close to the surface of the body is unduly exposed to cold in winter and to atmospheric heat and hot rays of the sun in summer. A serious objection to the conventional form of unionsuit is that because of the excessive weight of the garment required for protection against the cold, the wearer is uncomfortable in the warmth of the home after being for a period outdoors.

The present invention comprehends an undergarment having incorporated therewith a pad for protecting the spine against cold in winter and hot rays of the sun in summer, the pad being relatively narrow of a size to extend well over the spine throughout the full length thereof, and of a thickness to afford the additional protection required therefor so that the undergarment may be of lighter weight than would otherwise be worn to suit the season's temperature conditions, providing for the comfort of the wearer in the house as well as outdoors, serving as a material aid in safeguarding the health, and entirely overcoming the objection hereinbefore referred to regarding the conventional form of heavy weight unionsuit required for winter wear.

A particular important novel feature of the invention resides in the special construction of protective padding provided, formed from a continuous piece of fabric and having at opposite sides of its longitudinal medial line a plurality of longitudinal folds forming outer, intermediate and inner layers of fabric extending from its side edges to the medial line of the pad. This particular construction affords an efficient, satisfactory protecting pad of simple, inexpensive construction that can be easily applied to the undergarment, that presents no raw edges to cause discomfort and which serves to stabilize the unionsuit, lending it balance in weight and a finished pleasing appearance, and offers no difficulty in the ready laundering of the garment.

Another important novel characteristic of the invention lies in the particular construction of pad referred to and the connection of the same to the garment which provides for relative movement between the layers of fabric and ballooning action thereof so that there is plenty of flexibility and give to the back of the garment preventing the neckband of the garment from being disagreeably tightened and the drawer legs working up when the wearer bends over, the particular

2

construction providing a garment having incorporated therewith an efficient protecting pad for the spine, that will allow perfect freedom of movement by the wearer and will be comfortable and satisfactory in use.

An object of the invention is to provide an improved unionsuit having a protecting pad for the spinal column of simple, inexpensive construction that can be easily applied to unionsuits of conventional form and that will be efficient in use.

Another object of the invention is to provide an improved unionsuit provided with a protective pad for the spine having a plurality of layers of fabric so formed and connected to the back of the unionsuit as to provide for relative movement between the layers of fabric and ballooning action of the same whereby while the pad is composed of several layers, the same will be resilient in use, and there will be ample give in the back of the garment so that the neckband of the garment will not be drawn uncomfortably tight and the legs of the garment will not work up when the wearer bends over, the construction providing for a comfortable satisfactory fit allowing full freedom of movement by the wearer.

Another object of the invention is to provide an improved garment having a spine protective pad of the character referred to, which will not present any raw edges to cause discomfort and which will readily conform to the contours of the back and fit comfortably thereagainst.

Another object of the invention is to provide an improved garment having a protective pad of the character referred to that will present a neat finished appearance and which will not interfere with the ready laundering of the garment.

The invention, with other objects and advantages thereof and the particular construction, combination and arrangement of parts comprising the same will be understood from the herein-after contained detail description when considered in connection with the accompanying drawings forming part hereof and illustrating one embodiment of the invention.

In the drawings:

Fig. 1 is a front elevation of a unionsuit provided with a spine protecting pad in accordance with the invention, parts of the garment being shown broken away, and the front open to expose the protective pad;

Fig. 2 is a plan view of the blank from which the pad is constructed;

Fig. 3 is a transverse section, on an enlarged scale, on the line 3—3 of Fig. 1;

Fig. 4 is a longitudinal section on the line 4—4 of Fig. 1;

Fig. 5 is a perspective view of the pad folded from the blank shown in Fig. 2 with the layers separated from each other;

Fig. 6 is a perspective view of the pad taken from the other side of the pad from that of Fig. 5.

Referring to a detailed description of the particular embodiment of the invention illustrated in the drawings, A designates a conventional form of unionsuit. The protective pad, generally designated B, as shown in Fig. 1 of the drawings, is relatively long and narrow and is applied to the inner face of the back 1 of the garment intermediate the width thereof, the pad extending longitudinally and being of a size to fully cover the spinal column. The pad comprises a strip of fabric provided at opposite sides of its medial line with a plurality of longitudinal folds forming an outer layer 2, an intermediate layer 3 and an inner layer 4 extending from its side edges to the medial line of the pad, the pad being constructed from a continuous piece of fabric. The blank b, shown in Fig. 2 of the drawings, from which the pad is formed, is folded inwardly along the lines c, d, e and f to the form shown in Fig. 5. The intermediate layers 3 and inner layers 4 of the pad are connected with each other along their inner marginal portions 12 and 13 by a row of stitching 5. Another row of stitching 14 runs from front to rear through the pad along the longitudinal medial line thereof into the layers back of the outer layers 2. The pad is applied to the garment with the innermost layers 4 disposed next to the inner face of the back 1 of the garment. The inner layers 4 of the pad are connected at their outer side marginal portions to the back of the undergarment by longitudinal lines of stitching 6 and 7, the intermediate and outer layers being left free from connection to the garment at their inner marginal portions and free at their outer side marginal portions from the outer side marginal portions of the innermost layers 4, this arrangement providing for relative lateral play between the layers and for free flexing of the pad so as to allow for perfect freedom of movement of the wearer when stooping over, and the flexibility of the pad permitting the same to conform to the contours of the back of the wearer.

The several layers of the pad are secured along their upper marginal edge portions to the garment at the neck portion thereof by stitching 8, and the intermediate and outer layers are connected along their lower marginal portions by stitching 10 and 11.

The undergarment A and pad B may be constructed of any suitable material such as cotton or wool, the character and weight of material selected for the garment and pad depending upon the season of the year.

By the particular construction and arrangement of parts hereinbefore set forth, a pad of simple, inexpensive construction is provided that can be easily applied to the conventional form of unionsuit, that will permit relative play and ballooning action of the layers so that the back of the garment will be freely flexible and allow perfect freedom of movement of the wearer in bending over. The pad will function efficiently to furnish the additional protection required for the spine against climatic conditions so that undergarments may be of lighter weight than would otherwise be required to suit particular temperature conditions, providing for the comfort of the

wearer in the home as well as outdoors, and being a material aid in preventing such ailments as lumbago, pneumonia, colds and heat prostrations attributable to undue exposure of the spine, the padding also serving to protect the spine against undue pressure and shock due to contact with unyielding objects.

While a preferred embodiment of the invention is illustrated in the drawings, it will be understood that minor changes and modifications may be made in the particular construction shown, and the invention may be embodied in other forms as will appeal to those skilled in the art and falling within the scope of the appended claims without departing from the spirit of the invention. Instead of attaching the protective pad to the garment, as shown in the drawings, with the layers 4 disposed next to the inner face of the back of the garment, the pad may be applied to the garment with its reverse side disposed next to the inner face of the garment. The strip forming the pad is in effect a modified box pleat construction.

I claim:

1. A protective pad for the spine adapted to be applied to the inner face of the back of an undergarment intermediate the width thereof and to extend longitudinally thereof to cover the spinal column, said pad comprising a strip of fabric provided at opposite sides of its longitudinal medial line with a plurality of longitudinal folds forming a plurality of layers of fabric extending from its side edges to the medial line of the pad.

2. A protective pad for the spine adapted to be applied to the inner face of the back of an undergarment intermediate the width thereof and to extend longitudinally thereof to cover the spinal column, said pad comprising a strip of fabric provided at opposite sides of its longitudinal medial line with a plurality of longitudinal folds, the strip being first folded inwardly and said folded portions then folded outwardly, forming three layers of fabric extending from its side edges to the medial line of the pad, the intermediate and the layers formed by the last folds being connected with each other along their inner marginal edge portions.

3. An undergarment provided with a protective pad for the spine applied to the inner face of the back of the garment intermediate the width thereof and extending longitudinally thereof to cover the spinal column, said pad comprising a strip of fabric provided at opposite sides of its longitudinal medial line with a plurality of longitudinal folds forming outer, intermediate and inner layers of fabric extending from its side edges to the medial line of the pad, the intermediate and inner layers being connected with each other along their inner marginal edge portions, the pad being arranged with its innermost layers disposed next to the inner face of the garment, and the innermost layers being secured along their outer marginal edge portions to the garment, said layers of material throughout the length thereof below their upper edges being entirely free from connection with the back of the garment except for said connection of the innermost layers along their outer marginal portions.

4. An undergarment provided with a protective pad for the spine applied to the inner face of the back of the garment intermediate the width thereof and extending longitudinally thereof to cover the spinal column, said pad comprising a strip of fabric provided at opposite sides of its longitudinal medial line with a plurality of lon-

itudinal folds forming outer, intermediate and inner layers of fabric extending from its side edges to the medial line of the pad, the outer, intermediate and inner layers being connected with each other along their inner marginal edge portions, the pad being arranged with its innermost layers disposed next to the inner face of the garment, and the innermost layers being secured along their outer marginal edge portions to the garment, said layers of material throughout the length thereof below their upper edges being entirely free from connection with the back of the garment except for said connection of the innermost layers along their outer marginal portions.

5. An undergarment comprising shirt and drawers combined provided with a protective pad for the spine applied to the inner face of the back of the garment intermediate the width thereof and extending longitudinally thereof to cover the spinal column, said pad comprising a strip of fabric provided at opposite sides of its longitudinal medial line with a plurality of longitudinal folds forming outer, intermediate and inner layers of fabric extending from its side edges to the medial line of the pad, the outer, intermediate and inner layers being connected with each other along their inner marginal edge portions, the pad being arranged with its innermost layers disposed next to the inner face of the garment, and the innermost layers being secured along their outer marginal edge portions to the

garment, said layers of material throughout the length thereof below their upper edges being entirely free from connection with the back of the garment except for said connection of the innermost layers along their outer marginal portions.

6. A protective pad for the spine adapted to be applied to the inner face of the back of the garment intermediate the width thereof and extending longitudinally thereof to cover the spinal column, said pad comprising a strip of fabric provided at opposite sides of its longitudinal medial line with a plurality of longitudinal folds, the strip being first folded inwardly and said folded portions then folded outwardly, forming three layers of fabric extending from the side edges of the pad to the medial line thereof, the several layers being connected with each other along their inner marginal edge portions.
